ATTORNEY

UNITED STATES PATENT OFFICE

137,984

DESIGN FOR A TELEPHONE HANDSET

Ernest S. McLarn, Manhasset, N. Y., assignor to
International Standard Electric Corporation,
New York, N. Y., a corporation of Delaware

Application April 11, 1944, Serial No. 113,226

Term of patent 14 years

(Cl. D26—14)

To all whom it may concern:

Be it known that I, Ernest S. McLarn, a citizen of the United States, residing at Manhasset, in the county of Nassau and State of New York, have invented a new, original, and ornamental Design for Telephone Handsets, of which the following is a specification, reference being had to the accompanying drawing, forming part thereof.

Figure 1 is a side elevational view of a telephone handset showing my new design;

Figure 2 is a plan view of the handset with the

receiver and transmitter casings facing downwards;

Figure 3 is a plan view of the handset with the receiver and transmitter casings facing upwardly;

Figure 4 is an end elevational view of the handset.

I claim:

The ornamental design for a telephone handset, as shown.

ERNEST S. McLARN.
